DESIGN.

C. T. GROSJEAN.
SPOON, FORK, OR KNIFE HANDLE.

No. 15,717.

Patented Jan. 13, 1885.

UNITED STATES PATENT OFFICE.

CHARLES T. GROSJEAN, OF NEW YORK, N. Y., ASSIGNOR TO TIFFANY & CO.,
OF SAME PLACE.

DESIGN FOR A SPOON, FORK, OR KNIFE HANDLE.

SPECIFICATION forming part of Design No. 15,717, dated January 13, 1885.

Application filed October 14, 1884. Term of patent 14 years.

To all whom it may concern:

Be it known that I, CHARLES T. GROSJEAN, a citizen of the United States, residing in the city, county, and State of New York, have invented and produced a new and original Design for a Spoon, Fork, or Knife Handle, of which the following is a specification, reference being had to the accompanying drawings, forming part thereof.

10 The head of the handle of the spoon, fork, or knife is of the general form of a violin, with three lines of beading around the edge. This on the front surface of the spoon and fork breaks into leaf-work, commencing at the top 15 and extending part way down, where the head joins the shank. The lines of the edge terminate at the base of the head in rosettes, with a leaf above and below. There is only a single raised line along the edge of the shank 20 to where an upright double leaf connects it with the bowl, prongs, or blade. The face of the spoon or fork at the top is a convex surface. The back is slightly concave, with the three lines, but without the leaf-work of the 25 front. Otherwise the back is nearly the same as the front, except that it has a honeysuckle-shell-like ornament connecting it with the rounded part of the bowl or prongs in the case of the handle being that of a fork. The knife-handle is the same on both sides and lacks the honeysuckle ornament.

In the drawings, Figure 1 is a view of the front surface of a spoon on the handle of which is placed my design. Fig. 2 is a view of the 35 reverse surface thereof. Fig. 3 is a view of the front surface of a fork on the handle of which is placed my design. Fig. 4 is a view of the reverse side of the fork. Fig. 5 is a side view of a knife on the handle of which 40 is placed my design.

a a a are the three lines around the violin-shaped head of the handle. These lines may be more or less in number, although the effect may not be greatly changed. Still I prefer this number. *b b* is the leaf-work which these lines break into on the front surface of the spoon, as shown in Figs. 1, 3, and 5. *c c* are the rosettes, the point of termination of said lines at base of the head; *d d'*, the leaves placed 45 above and below this point of termination, *d* being in the head, and *d'* on the upper portion of the shank. *e* is the single raised line

along each edge of the shank down to the upright double leaf *f* at base of the shank, where it meets the bowl of spoon or prongs of fork. *g* is the convex surface on front surface of the handle. *h* is the concave surface on reverse side thereof. *i* is the honeysuckle ornament connecting the shank with the rounded part of bowl or prongs.

I claim—

1. A design for a spoon, fork, or knife handle, consisting of a violin-shaped head, *h*, containing a border of raised lines, *a a*, said lines breaking into leaves *b b*, as shown and described.

2. A design for a spoon, fork, or knife handle, consisting of a violin-shaped head, *h*, containing a border of raised lines, *a a*, said lines breaking into leaves *b b*, and inclosing a convex surface, *g*, contained within said lines, as shown and described.

3. A design for a spoon, fork, or knife handle, consisting of a violin-shaped head, *h*, containing a border of raised lines, *a a*, said lines breaking into leaves *b b*, and inclosing a convex surface, *g*, together with rosettes, and leaves above and below such rosettes, as shown and described.

4. The design of spoon, fork, or knife handle, consisting of a violin-shaped head, *h*, containing a border of raised lines, *a a*, said lines breaking into leaves *b b*, and inclosing a convex surface, *g*, together with rosettes *c c* at the base of such head, and leaves above and below the rosettes, and a shank containing a border of a single raised line, *e*, terminating at the bowl, prongs, or blade in an upright double leaf, *f*, as shown and described.

5. The design of spoon or fork handle, with a back consisting of a violin-shaped head *h*, containing a border of raised lines, *a a*, inclosing a slightly-concave surface, *h*, together with rosettes *c c* at the base of such head and leaves *d d'* above and below the rosettes, and a shank containing a border of a single raised line, *e*, terminating at the rounded part of the bowl or prongs in an upright double leaf, *f*, and a honeysuckle-shell-like ornament, *i*, as shown and described.

CHARLES T. GROSJEAN.
